(57) **CLAIM**

The ornamental design for a therapeutic eye mask, substantially as shown and described.

DESCRIPTION

FIG. 1 is a perspective view of a therapeutic eye mask according to an example embodiment of the design, showing an example application and environment of use over the eye region of a person.

FIG. 2 is a perspective view of the therapeutic eye mask shown in FIG. 1.

FIG. 3 is a side view of the therapeutic eye mask shown in FIG. 1 (the opposite side views being mirror images of one another).

FIG. 4 is a front view of the therapeutic eye mask shown in FIG. 1.

FIG. 5 is a back view of the therapeutic eye mask shown in FIG. 1.

FIG. 6 is a top view of the therapeutic eye mask shown in FIG. 1.

FIG. 7 is a bottom view of the therapeutic eye mask shown in FIG. 1.

FIG. 8 is an enlarged cross-sectional view of the therapeutic eye mask shown in FIG. 1, taken at section line 8-8 in FIG. 5; and,

FIG. 9 is an enlarged cross-sectional view of the therapeutic eye mask shown in FIG. 1, taken at section line 9-9 in FIG. 5.

In the drawings, the broken lines depict environmental subject matter only and form no part of the claimed design.
